United States Patent Office.

J. W. LEWIS, OF OREGON CITY, OREGON.

Letters Patent No. 91,644, dated June 22, 1869.

IMPROVEMENT IN ROLLER-CUTTERS FOR PLOWS.

The Schedule referred to in these Letters Patent and making part of the same.

To all whom it may concern:

Be it known that I, J. W. LEWIS, of Oregon City, in the county of Clackamas, and State of Oregon, have invented a new and useful Improvement in Roller-Cutters for Plows; and I do hereby declare that the following is a full, clear, and exact description of the same, reference being had to the accompanying drawings, forming a part of this specification, in which is represented a side view of a roller-cutter for plows constructed according to my improvement, different letters of reference indicating the several parts thereof.

The invention consists in the novel construction of a roller-cutter for plows, whereby means of adjustment, both lateral and vertical, are provided to the same.

In order that others may understand the construction and operation of my invention, I will proceed to describe it with reference to the drawings.

A is an ordinary roller-cutter, suspended upon a bearing supported between the lower extremities of two curved arms B B.

Said curved arms B B are united at their upper extremities, and form a consolidated neck, which fits through and is riveted into a bearing or socket, b, so as to form a swivel-joint at that point, thereby providing a means of lateral adjustment to the cutter, so that the same may accommodate itself to the turnings of the plow, all of which is substantially after the ordinary manner of constructing roller-cutters of this character.

Extending upwardly and outwardly from opposite

sides of the swivel-socket b, are curved braces C C', by means of which the cutter is connected with the beam of the plow.

Through the upper extremity of one of these braces C is provided an opening or pivot-hole, c, while through the upper and central portion of the other is provided a curved slot, e.

The ends of the braces C C' are caused to pass through vertical mortises cut through the beam of the plow, and are secured therein by pins or bolts passing laterally through the beam and the openings c and e of the said braces.

The vertical adjustment of the cutter A is effected by the sliding of the slotted brace C' through its mortise in the beam, the other brace, C, turning upon its pin or bolt as a pivot.

By this means the cutter may be raised or lowered at will, for cutting deep or shallow, as necessity may require.

A thumb-screw or other suitable means may be adopted for confining the slotted brace C' to any adjustment.

What I claim as my invention, and desire to have secured by Letters Patent, is—

A roller-cutter for plows, consisting of a roller, A, arms B B, swivel-joint b, and braces C C', substantially as herein described.

J. W. LEWIS.
